UNITED STATES PATENT OFFICE

165,781

SMOKER'S STAND OR SIMILAR ARTICLE

William C. Panzer, Chicago, Ill.

Application January 31, 1951, Serial No. 14,052

Term of patent 14 years

(Cl. D85—2)

To all whom it may concern:

Be it known that I, William C. Panzer, a citizen of the United States, residing in Chicago, Cook County, Illinois, have invented a new, original, and ornamental Design for a Smoker's Stand or Similar Article, of which the following is a specification, a reference being had to the accompanying drawings, forming a part hereof.

Figure 1 is a side elevational view of a smoker's stand or similar article, showing my new design;

The stippling shown is intended to represent a color therefor contrasting with the color of the parts not so stippled.

I claim:

The ornamental design for a smoker's stand or similar article, substantially as shown and described.

WILLIAM C. PANZER.
